COLLECTION RECEPTACLE FOR VACUUM
CLEANERS

Wilbur V. Paine, East Hartford, Conn., assignor
to The Spencer Turbine Company, Hartford,
Conn., a corporation of Connecticut

Application November 22, 1939, Serial No. 305,659

2 Claims. (Cl. 232—1)

My invention relates to the class of apparatus commonly employed for vacuum cleaning purposes or for conveying dirt laden air in apparatus of various sorts, the invention relating more particularly to the mechanism for final disposition of the dust separated from the air in such apparatus, and an object of the invention, among others, is to provide ready and efficient means for removal and replacement of the receptacles, as dust cans, employed to receive the dust and dirt collected by the separators and comprising a part of the apparatus above mentioned.

One form of an apparatus embodying my invention and in the construction and operation of which the objects herein set out, as well as others, may be attained is illustrated in the accompanying drawing, in which—

Figure 1 is a view in side elevation of the lower part of a vacuum cleaning apparatus embodying my invention.

Figure 2 is an end view from a point located at the right of Figure 1 but omitting the dust can.

Figure 3 is a view in horizontal section on a plane denoted by the broken line 3—3 of Fig. 1, but showing the dust can partially removed.

Figure 4 is a view in horizontal section on enlarged scale on a plane denoted by the broken line 4—4 of Fig. 2 with the dust can partially broken away to show construction.

My invention, while not limited to use with vacuum cleaning apparatus of any particular sort, is especially applicable to portable apparatus of this type and for this reason such has been illustrated in the drawing herein for the purpose of disclosing my invention, in the accompanying drawing the numeral 6 denoting a platform supported by wheels 7 at the front and by wheels 8 at the back. A vacuum producer 9 is mounted on the front part of the platform, this embodying a motor 10, and a separator 11 united with the vacuum producer is supported by the back end of the platform. All of the parts thus far described are of common and well known construction and further and detailed illustration and description are therefore omitted herein.

The separator is in the form of a case or shell containing the separating elements of any well known and common construction, and in adapting my invention this shell is formed with a recess 12 at the bottom thereof and in a downward extension 13 of generally curved form but with flat opposing sides forming recesses 14 within which is contained operating mechanism to be presently described.

5 A dust can 15 is formed for reception in the recess 12, this can being provided on its bottom with swivel casters 16 and with a handle 17 in the form of a ring extending around the can intermediate its top and bottom ends and rigid with lugs 18 secured to and projecting from the sides of the dust can, the handle being thus spaced from the can to permit the fingers of a person to readily grasp the ring for the purpose of handling the can.

10 The upper end of the can 15 is provided with a shouldered lip 19 to rest upon one end of each of two lifting levers 20, the opposite ends of said levers each being pivotally mounted in one of the flat supporting sides of a recess 14, thereby positioning said levers on opposite sides of the extension 13. A lifting and locking cam 21 is pivotally supported in each of the recesses 14, thereby locating said cams on opposite sides of the can 15 and inside of the recesses 14, the edges 15 of said cams each encountering a hub 23' adjacent a roller 23 mounted on a stud 22 projecting inwardly from the free end of each of the levers 20 for engagement with the lip 19 on the can, as shown in dotted lines in Fig. 1 of the drawing. The pivots of the cams 21 extend through flat supporting sides of the recesses 14, the cams being located inside of said recesses and said pivots comprising shafts 24 rotatably mounted in said recesses. A dust can lifting lever 25 in the form of a bail is secured at its opposite ends to the shafts 24, said lever extending substantially half way around the can. When in its lowered position as shown in Fig. 1 this lever crowds the cams 21 against the hubs 23' forcing the rollers 23 into contact with the lip 19 and thereby securely holding the can in its raised position tightly against the under surface of the separator 11. When the lever is raised to the position shown in Fig. 2 the can will be lowered to rest upon its casters 16 and then by grasping the handle 17 the can may be removed from within its recess and taken to any desired location for dumping the contents therefrom. The handle 17, above referred to, not only serves as a means for handling the can but further serves an important feature as a guide for movement of the can into the recess 12, such handle being of a diameter to fit within the walls of the recess 12 and thereby correctly position the can when it is pushed into the recess.

15 In accordance with the provisions of the patent statutes I have described the principles of operation of my invention, together with the device which I now consider to represent the best

embodiment thereof; but I desire to have it understood that the device shown is only illustrative and that the invention may be carried out by other means and applied to uses other than those above set out.

I claim:

1. In a device of the character described comprising a chambered shell having an opening through the bottom thereof, a receptacle of bulky and weighty characteristics inconvenient for manual handling, a recess receiving and supporting portion forming part of and extending from the bottom of said shell and having a bottom and a side both opening into the recess therein for the reception of the upper portion of said receptacle, and lever lifting means mounted in the opposite side walls of said receiving and supporting portion and engageable with lever abutment means formed on the exterior of the upper portion of said receptacle to lift the latter into contact with the bottom of said chambered shell, said lever lifting means including a lever of bail form extending exteriorly of the shell with its opposite ends pivotally mounted in

the side walls of said receiving and supporting portion.

2. In a device of the character described comprising a chambered shell having an opening through the bottom thereof, a receptacle of bulky and weighty characteristics inconvenient for manual handling, and having a shouldered flange at its upper edge, a recessed receiving and supporting portion forming part of and extending from the bottom of said shell and having a bottom and a side both opening into the recess therein for the reception of the upper portion of said receptacle, lever lifting means mounted in the opposite side walls of said receiving and supporting portion and engageable with said shouldered flange, a lever of bail form having its opposite ends mounted in opposite side walls of said receiving and supporting portion, and an operative connection between said bail lever and the levers engageable with the flange on the upper end of said receptacle to lift the receptacle into contact with the bottom of said chambered shell.

WILBUR V. PAINE
